UNITED STATES PATENT OFFICE.

BENJAMIN W. DAVIS, OF CHICAGO, ILLINOIS.

PORTABLE SIGNAL SYSTEM.

1,346,531.

Specification of Letters Patent. Patented July 13, 1920.

Application filed March 28, 1916. Serial No. 87,182.

To all whom it may concern:

Be it known that I, BENJAMIN W. DAVIS, a citizen of the United States, residing at Chicago, in the county of Cook and State 5 of Illinois, have invented certain new and useful Improvements in Portable Signal Systems, of which the following is a specification.

My invention relates in general to portable lighting systems, and more particularly to a signal system for use in controlling traffic at street intersections.

In large cities where the traffic is heavy, it is customary to place at street intersections traffic policemen who control the movement of vehicles in intersecting directions by means of whistles or by signaling with their arms. The use of whistles is frequently confusing, and must usually be supplemented by the traffic policeman indicating with his arms the desired movement of the vehicles. Semaphores have been employed in some cities, and it has been proposed to use signal lights at traffic intersections. These systems are particularly advantageous where the traffic is so heavy that manual signals given by a policeman cannot be seen by all of the drivers of vehicles and by all pedestrians. In such systems, 30 however, it is necessary that the semaphores and lights should be operated by the policeman who controls the traffic, and it has therefore been found more satisfactory where the traffic is not too heavy for the policeman to control the traffic directly by the movement of his arms.

The primary object of my invention is to provide a portable light signal system which may be conveniently attached to one 40 whose duty it is to operate the signal, and which will, upon raising or lowering of the limb of the operator, be automatically so controlled as to give the desired signal.

A further object of my invention is to 45 provide a signal system comprising electric lights adapted to be attached to the body of the operator, and so arranged that upon the operator lifting his arm to a substantially horizontal position the circuit will be closed to the electric lights, and upon lowering his arm to a substantially vertical position the circuit to the lights will be broken, thereby rendering it possible for the operator to control the lights so as to give the 50 desired signal by the same movement of his

arms which would indicate the signal were his arms visible.

A further object of my invention is to provide a signal system for controlling traffic at street intersections which will be 60 simple in construction, convenient in use, and efficient in operation.

A further object of my invention is to provide a lighting system which may be attached to the body of a person, and which 65 will automatically illuminate and darken predetermined lights upon certain movements of the limbs of the person.

Still another object of my invention is to provide a novel form of liquid switch for 70 controlling an electric circuit.

My invention will be more fully disclosed hereinafter with reference to the accompanying drawings in which the same is illustrated as embodied in a convenient and 75 practical form, and, in which,—

Figure 1 is an elevational view of a traffic policeman equipped with my invention.

Fig. 2 is a slightly modified form of my invention attached to the arm of a person. 80

Fig. 3 is a diagrammatic view of the electric circuit when the arm of the person to which it is attached is in a substantially vertical position.

Fig. 4 is a similar view of the electric 85 circuit when the arm of the person to which it is attached is in a substantially horizontal position.

Fig. 5 is an enlarged sectional view of my improved liquid switch when in circuit- 90 closing position.

Fig. 6 is a sectional view, taken on the line 6—6 of Fig. 5.

Fig. 7 is a view similar to Fig. 5, showing the switch in circuit-breaking position; 95 and

Fig. 8 is a large perspective view of the means for securing to the limb of the operator the lights, battery, and switch comprising the signal circuit. 100

Similar reference characters are used to designate similar parts in the several figures of the drawings.

Reference characters A' and A² indicate incandescent lights of any desired color, 105 preferably red. B' and B² indicate straps to which the lights A' and A² are connected, and which are adapted to be secured around the arm of the operator in spaced relation to each other. C indicates a bat- 110

tery which is secured to a strap B^3 , adapted to be extended around the arm of the operator. D indicates a switch for automatically controlling the circuit from the battery to the lights, according to the position of the arm of the operator. B^4 indicates a strap to which the circuit closer is attached, and which may also be secured to the arm of the operator. The several straps B' , B^2 , B^3 , and B^4 may be conveniently attached together by a longitudinal strap B , which may extend along the back of the arm of the operator, as shown in Fig. 1, or along the front of the arm, as shown in Fig. 2. Preferably both arms of the operator are provided with a signal system such as above described, inasmuch as in controlling street traffic it is frequently necessary for the policeman to use both arms.

In order that the position of the traffic policeman may be at all times visible, and his safety thereby promoted, electric lights may if desired be secured to him, as, for instance, upon his shoulders, which are continually illuminated. E indicates one of such lights. As shown in Fig. 1, one of said lights is preferably located on each shoulder of the policeman, and they are preferably white in color.

While any suitable automatic switch may be used for closing the circuit to the lights when the arm of the policeman is in a substantially horizontal position, and for breaking the circuit when his arm is in a substantially vertical position, yet I preferably use a liquid switch of the construction illustrated in detail in Figs. 5, 6, and 7. The casing of the switch is preferably formed in three sections, and is made of any suitable non-conducting material, such, for instance, as hard rubber, or glass. The central section is preferably cylindrical in form, and is provided with screw threads around the opposite ends thereof, with which engage screw threads within end sections D' and D^2 . In some instances it may be desirable to make the casing of the switch air-tight, so that a vacuum may be maintained therein, inasmuch as the presence of air serves to more rapidly deteriorate some conductors. Openings surrounded by circular flanges d' and d^2 extend through the ends of the central section of the casing, so that the interior of such central section is placed in connection with the interior of the end sections.

Inclosed within the casing is a liquid which is a good conductor of electricity, such, for instance, as mercury. The quantity of the liquid is such that when the casing is in the horizontal position shown in Fig. 5 it will be at a level above the bottom of the openings made by the flanges d' and d^2 , while when the casing is in a vertical position, as shown in Fig. 7, the liquid will not extend upwardly through the central section

into the top section of the casing. Located in each of the end sections D' and D^2 , adjacent the ends of the central section, are rings H' and H^2 , formed of suitable conducting material, and with which communicate conducting wires forming the circuit which is to be controlled. It will be observed that the rings H' and H^2 are at all times in contact with portions of the liquid conductor regardless of the position of the switch, inasmuch as the flanges d' and d^2 retain portions of the liquid conductor within the end compartments in which are located the said conductor rings. When the casing of the switch is cylindrical, as shown in the drawings, it may be placed in any position and it will work equally well, thereby avoiding the necessity of locating the casing with a certain portion of it located in any predetermined position.

When the arm of the operator is in a substantially vertical position, the circuit controller will break the circuit to the lamps, inasmuch as the liquid in the switch does not extend continuously from one of the rings H' to the other ring H^2 . When, however, the arm of the operator is lifted to substantially horizontal position the liquid will electrically connect both of the rings, and thereby close the circuit to the lamps. It will be seen that when the switch is moved from a vertical to a horizontal position the circuit is completed through the lower portion of the liquid flowing into contact with the upper portion of the liquid thereof, and not by means of the mercury connected with one lead flowing into contact with a metal conductor connected with the other lead of the circuit. When mercury is used as the liquid circuit closing conductor the injurious effect upon it and upon the metal conductors, such as the rings H' and H^2 , due to the circuit being closed by the movement of the mercury into contact with the metal conductors, is avoided, as the circuit is closed by portions of the mercury flowing into contact with each other and is broken by the mercury separating, as indicated in Fig. 7 of the drawings.

The safety lights E upon the shoulders of the operator are preferably located in a separate circuit from the lamps A' and A^2 , so that they may continue to be illuminated when the signal lights are dark. If desired, a mechanical switch, such as indicated diagrammatically at F , Figs. 3 and 4, may be provided for controlling the circuit of the shoulder lamps. If desired, also, a separate battery may be provided for each shoulder lamp, as indicated in Fig. 2, in which C' indicates a battery mounted directly upon the shoulder of the operator adjacent the lamp with which it is in circuit.

While I have illustrated and described my invention as particularly adapted for use by

a traffic policeman, yet it will be understood that it is capable of more general uses, one being that it may be attached to a person who desires to illuminate or darken lights placed upon his or her body through the movement of the arms or legs.

- 5 The location of the two lights in spaced relation upon the arm of the operator serves to indicate the position of the arm by the 10 relative positions of the lights, that is, when the lights are in horizontal alinement the arm of the operator is in a lateral position, and when the lights are in vertical alinement the arm of the operator is in lowered 15 position. It would be practical in some instances to allow the lights to be continually illuminated, as the relation of the two spaced lights would indicate the desired signal.
- 20 When my invention is used for controlling street traffic, it will be seen that it enables the traffic policeman to regulate the traffic at night by the same movements of his arms as regulate the traffic in the daytime, 25 when his arms are visible. It will be further evident that by my invention the traffic policeman may move about to more efficiently regulate the traffic, and he does not have to stand at a given point as is the case 30 where stationary signals are provided.

I claim:

1. In a portable signal system, the combination

35 nation with a battery, of a plurality of electric lamps, means for supporting said lamps in spaced relation upon the arm of an operator, an automatic switch secured to the arm of the operator for controlling said circuit upon predetermined movements of the operator's arm, another lamp mounted upon the operator, and a normally-closed circuit 40 for said last-mentioned lamp.

2. In a portable signal system, the combination with a source of electricity, of an electric lamp, a circuit therefor, means for supporting said lamp and circuit upon the 45 arm of an operator, an automatic switch secured to the arm of the operator controlling said circuit upon predetermined movements of the operator's arm, another lamp mounted upon the operator, a circuit for said last- 50 named lamp, and a switch for controlling said last-mentioned circuit.

3. In an electric signal system, the combination with a source of electricity, of a plurality of electric lights, a circuit, a 55 switch, and means for supporting said plurality of lights in spaced relation upon a limb of an operator so that the movement of said limb to different positions effects through the operation of the switch a different relation between the said lights.

In testimony whereof, I have subscribed my name.

BENJAMIN W. DAVIS.
